CLAIM

The ornamental design for a fastening device, as shown and described.

DESCRIPTION

FIG. 1 is a perspective view of a first embodiment of a fastening device embodying my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of a second embodiment of the fastening device;

FIG. 9 is a front view thereof;

FIG. 10 is a rear view thereof;

FIG. 11 is a left side view thereof;

FIG. 12 is a right side view thereof;

FIG. 13 is a top view thereof; and,

FIG. 14 is a bottom view thereof.

The superimposed areas and broken lines rendered in FIGS. 1, 6, 7, 8, 13 and 14 illustrates portions of the fastening device and form no part of the claimed design.
